UNITED STATES PATENT OFFICE.

CARL C. GRAY, OF MINNEAPOLIS, MINNESOTA, ASSIGNOR TO TWIN CITY SEPARATOR CO., OF MINNEAPOLIS, MINNESOTA, A CORPORATION OF MINNESOTA.

GRAIN CLEANING AND SEPARATING MACHINE.

Application filed February 8, 1926. Serial No. 86,934.

This invention relates to improvements in grain cleaning and separating machinery and the primary object is to provide a highly novel, practical and efficient machine for thoroughly cleaning and separating grain of all kinds. A further object is to provide an improved construction of scalper or cleaning mechanism which separates all or most of the foreign matter from the grain before it is advanced to the separating mechanisms which separate it into its constituent elements. A further object is to provide means of a novel nature for feeding and distributing grain, discharged by the cleaning process, to a series of separating units whereby the distribution of grain to the various units will be automatically regulated and equalized. A further object is to associate said feeding and distributing means with the cleaning and separating mechanisms whereby the capacity of the machine may be regulated at will, and whereby the volume of grain discharged by the cleaning unit will determine and regulate the receiving capacity of the respective separating units. Further and more specific objects will be disclosed in the course of the following specification, reference being had to the accompanying drawings, in which:

Fig. 1 is a front elevation of the machine.

Fig. 2 is a side elevation of the machine as seen from the right in Fig. 1, some parts being broken away for purpose of illustration.

Fig. 3 is a left end elevation of the machine, with various parts broken away for purpose of illustration.

Fig. 4 is a sectional elevation as on the line 4-4 in Fig. 1.

Fig. 5 is a sectional plan view as on the line 5-5 in Fig. 2.

Fig. 6 is a detail perspective view of the major portion of the feed regulating and adjusting mechanism, as seen when removed from the machine.

Fig. 7 is a rear view of the left end of the machine, with various parts being broken away for purpose of illustration.

Fig. 8 is a left end elevation of the machine, with certain parts broken away.

Referring to the drawings more particularly and by reference characters 9 designates a main frame structure of a grain separator having two or more grain separat-

ing units. In the present instance three of such separating units A, B, and C are indicated, but it will be understood that any number of units may be employed. The units in the present instance are indicated as of the well known cylindrical type, but these, per se, are notoriously old and form no part of the present invention. The grain is fed into these units by spouts 10, 11 and 12, and the flow of grain to the respective units is regulated by vertically slideable gates 13, 14 and 15. The gates have pins 16 which engage in the slotted ends of cam acting levers 17, 18 and 19, which levers are pivoted as at 20, and are simultaneously opened and closed by a bar 21 which extends across the machine. The bar 21 is reciprocated or adjusted by a hand lever 22, pivoted to the machine as at 23, so that when the lower end of the lever is pulled out the gates 13-15 will be opened, while the pressing in of the lever will tend to close or partly close the gates.

Carried on top of the main frame 9 is the scalper or cleaning mechanism, which may be described as follows: A casing having end walls 24 and 25 and a rear wall 26 is provided in its upper end with a hopper D into which the uncleaned and unseparated grain is fed, as by a chute or feed pipe E. The hopper D has a rear wall 27, spaced from the wall 26, a pair of inclined and spaced front shelves 28 and 29, and an inclined rear shelf 30. Said shelves slope inwardly and are spaced from each other in an offset manner so that the grain will pass through between them in a zig-zag manner. The object of this is to prevent the passage of any large sticks or other objects, which, when thus caught may be readily removed by hand, and to permit the operator to observe (between the members 28 and 29) the nature and amount of grain being fed to the cleaner proper. Under the rear shelf 30 is arranged a longitudinally ribbed feed roller 31, carried on a shaft 32, and it operates in conjunction with a series of gates or doors 33, 34 and 35 to determine and regulate the actual flow of grain from the hopper to the cleaning mechanism. These gates 33-35 are provided with contacting side members 36 to prevent the grain from escaping between the gates and restricting it to flowing over the rear or inner ends of the gates, as determined by the feed roller 31.

The gates are pivotally mounted for independent adjustment upon a shaft 37. This shaft is normally non-rotatable, but is subject to a slight oscillating movement when the machine is in operation. Upon the shaft 37 are rigidly secured collars 38, one for each gate, which are provided with depending tongues 39 in which rods 40 are slidably guided. The inner ends of the rods 10 are pivoted to the inner ends of the gates, and compression springs 41 are carried by the rods so as to hold the gates in a yielding upward position. The object of independently mounting the gates 33, 34 and 15 35 is to prevent the excessive feeding of grain to the shakers, when a corn cob or other object passes or lodges under the roller 31, that would occur if only one wide gate were employed. Upon one end of the 20 shaft 37 is secured a bell crank lever 42 which imparts to the shaft the oscillating movement previously indicated, and which will later be described. It may here be noted, however, that the lever 42 is connected to a spring 43 which tends to turn 25 the shaft 37 so as to open the gates 33-35.

As the grain leaves or falls from between the gates 33-35 and the feed roll 31 it drops down upon the inclined screen 44 of a shaker frame 45. This frame is provided with forwardly and rearwardly projecting plates 46 which ride on rollers 47 so that the frame may be oscillated from side to side. Under the rear portion of the screen 44 the frame 30 45 is provided with an inclined bottom 48. A link rod 49 is pivotally connected at one end to the shaker bottom 48 and at its other end is pivotally connected to one arm of a bell crank lever 50 which is pivoted, as at 35 51, to the scalper frame, the other arm being connected, as by a universal joint 52, to a connecting rod 53 which is reciprocated by an eccentric 54 on a shaft 55, mounted in bearings 56.

The shaft 55 has a pulley 57, by which it is driven from a line shaft or some suitable power unit, and a sprocket pinion 58, by which it drives a sprocket chain 59 which passes over a sprocket gear 60 on the feed 40 roller shaft 32. The shaft 55 is also provided with a pulley 61 which, by a belt 62, drives a small pulley 63 of a centrifugal suction fan the casing 64 of which has an inlet pipe 65 and a discharge pipe 66. The upper 45 end of the pipe 65 is flared or widened, and is connected and communicates with the upper end of the passage between the walls 27 and 26, so that it will cause a continuous blast or current of air to be taken in to the 50 machine and rearwardly to the pipe 66. As this current of air passes over the screen 44 and back through the stream of grain falling from the feed roller, it takes and carries with it all chaff, straw, dust and other undesirable foreign matter having a lighter spe-

cific gravity than the grain. A door 67 is provided in the wall 26, and is adjustable by a bracket 68, whereby the force or volume of the draft coming up from the lower end of the chute may be easily regulated. 70

Objects too large to go or be shaken through the screen 44 will slide or roll off, forwardly. The grain passing through the screen will drop directly into a long trough 69, or be guided into it by a plate 70, and from the trough 69 passes down through spouts 71, 72 and 73 which lead it directly into the respective separator unit spouts 10, 11 and 12. A worm 74, carried by the shaft 55, operates in the bottom of the trough 69 75 and has for its object to move the grain along to the left (as in Fig. 1) and thus deliver it to the different separating unit spouts. 80

Much of the construction above described 85 is substantially old in the art, and, as such, the most objectionable features have been that no adequate means have been provided for properly adjusting and distributing the flow of grain from the hopper D to the separating units, that no means have been provided for automatically cutting off or reducing the flow of grain discharged by the feed roller when the feed worm 74 and the trough 69 become crowded, and that no means have 90 been provided for automatically adjusting the discharged grain in proportion to the demands or capacity of the separator units, as set, or for manually setting and adjusting the various feeding and adjusting devices. 95 These objections have all been very effectively overcome by my invention, and particularly by virtue of the construction now to be set forth and described. 100

Slidably mounted in horizontal slots 75 in 105 the side walls of the trough 69, and near the left end thereof, is a bar 76, to which is secured a casting 76^a having a rod 77 which guides in a perforation 78 in the end wall of the trough. The casting is also provided 110 with depending arms 79 and 80, the first of which is vertical while the latter is inclined and is provided with a set screw 81 for adjustably limiting the outward swinging movement of a gate 82 which swings from the bar 76. The gate 82 is limited in its right or inward movement by the arm 79, and in its left or outward movement by the set screw 81. The gate operates adjacent to the end of the feed screw 74 and is provided 115 with a slot 83 through which extends the shaft 55. A link rod 84 is pivoted as at 85 to the right side of the gate 82, and, at its opposite end 86, to the depending arm 87 of a bell crank lever 87-88 which is pivotally 120 carried by a rigid or stationary bracket 89. The horizontal arm 88 of this bell crank lever is adjustably connected, to the horizontal arm of the bell crank lever 42, by a link 90 having an adjusting nut 91. The outer 125

end of the rod 77 is hooked, to engage the upper end of a hand lever 92 which is pivotally carried by a stationary bracket 93. The lower end of the handle 92 is provided with suitable means such as a pin 94, and a hook 95 for engaging the pin, to releasably hold the handle up adjacent to the machine; while the handle 22 is provided with an adjustable extension member 96, secured by a screw 97, to engage the lever 92 and move it in with the lever 22, but which permits the lever 22 to move outwardly without taking the lever 92 with it, when the latter is secured by the hook 95.

As previously mentioned the cleaned grain is fed into the trough 69 and is moved along by the worm 74 so that it will feed properly to the various separator units. Should the supply of cleaned grain exceed the capacity of the separating units, as set, then the spouts 10—12, 71—73 will become chocked with grain and the worm 74 will move the surplus grain in the trough 69 over against the gate 82, moving it to the left (as seen in Figs. 1 and 5), and as the gate swings leftward from the pivot rod 76, it pulls the rod 84 with it, and this, by virtue of the elements 86, 87, 88, 90, 91, and 42, rotates the shaft 37 in a direction which will tend to move the gates 33, 34 and 35 upward toward the roller 31, thus reducing the supply of grain being fed to the cleaning shaker. When the grain in the spouts has been absorbed by the separators to the extent that the spouts can receive more grain from the trough, then the volume of grain in the trough has been reduced to normal, the gate 82 will be returned to its initial position, by the spring 43, and the gate (33) springs 41 will be restored to their original pressure. The sensitiveness of the automatic adjustment just described may readily be regulated by the adjusting nut 91 on the link 90. The swinging movement of the gate 82 is limited by the set screw 81 of the bracket arm 80, and if the screw 81 does not permit the gate to swing sufficiently far, to effect the necessary adjustments, then the entire gate will move together with the rod 76 to pull the rod 84 still farther to the left. In this event also, the parts will be restored by the spring 43, when the grain yields, as the gate 82 abuts the arm 79 as soon as restored to vertical position.

To manually reduce and stop the volume of grain passing between the feed roll 31 and the gates 33—35, the operator merely pushes the hand lever 92 toward the machine where he may secure it as by the hook 95. This action pulls the rod 77 and consequently the rod 84, with the closing effect on the gates 33—35 already described. This is a very efficient manner of cleaning out the machine as it stops or substantially reduces the grain leaving the hopper D but does

not close any of the other grain parts, so that the grain may pass entirely through the machine.

If the operator desires to reduce but not cut off the volume of grain passing through the entire machine, so that it may be treated slower or more effectively he presses the hand lever 22 inward, thus closing or partly closing the separator unit gates 13, 14 and 15. He cannot reduce the separator unit capacity, however, without also reducing the cleaner capacity, because of the hook or extension 96 which engages the hand lever 92. As the member 96 is vertically adjustable on the lever 22, and as the levers 22 and 92 have different fulcrums, it is obvious that the degree of movement imparted to the lever 92 by the other lever may also be adjusted as circumstances may require.

It is understood that suitable modifications may be made in the general design and structural details of the invention as herein shown and described, provided, however, that said modifications come within the spirit and scope of the appended claims.

Having now therefore fully shown and described my invention, what I claim to be new and desire to protect by Letters Patent is:

1. The combination with a machine having a grain cleaning mechanism and a series of grain separating units adapted to receive cleaned grain from the cleaning mechanism, of gates for controlling the passage of grain to the grain cleaning mechanism, and means for adjusting said gates when the volume of cleaned grain exceeds the predetermined capacity of the separating units.

2. The combination with a machine having a grain cleaning mechanism and a series of grain separating units adapted to receive cleaned grain from the cleaning mechanism, of adjustable means for feeding grain to the cleaning mechanism, and means for automatically adjusting said feeding means according to the predetermined capacity of the separating units.

3. The combination with a machine having a grain cleaning mechanism and a series of grain separating units adapted to receive cleaned grain from the cleaning mechanism, of adjustable means for feeding grain to the cleaning mechanism, and means for automatically adjusting said feeding means according to the predetermined capacity of the separating units, said adjusting means being actuatable by the volume of grain discharged by said cleaning mechanism.

4. The combination with a machine having a grain cleaning mechanism and a series of grain separating units adapted to receive cleaned grain from the cleaning mechanism, of means for regulating the flow of grain to the cleaning mechanism, means for regulating the flow of grain to the separating units,

and means for simultaneously adjusting both of said regulating means.

5. The combination with a machine having a grain cleaning mechanism and a series of grain separating units adapted to receive cleaned grain from the cleaning mechanism, of means for regulating the flow of grain to the cleaning mechanism, means for regulating the flow of grain to the separating units and manually controlled means for simultaneously and correspondingly adjusting both of said regulating means to increase or decrease the volume of grain treated by the entire machine.

15 6. The combination with a machine having a grain cleaning mechanism and a series of grain separating units adapted to receive cleaned grain from the cleaning mechanism, of means for regulating the flow of grain to the cleaning mechanism, means for regulating the flow of grain to the separating units, and means actuatable by the grain passing from the cleaning mechanism to the separating units for automatically adjusting the 20 said first mentioned regulating means.

30 7. In a machine of the character described the combination with a grain cleaning mechanism and a series of grain separating units, of a feeding device for feeding grain to the cleaning mechanism, a receptacle for receiving grain from the cleaning mechanism and distributing it to the separating units, and means controlled by the volume of grain in said receptacle for adjusting the feeding 35 device.

40 8. In a machine of the character described the combination with a grain cleaning mechanism and a series of grain separating units, of a feeding device for feeding grain to the cleaning mechanism, a receptacle for receiving grain from the cleaning mechanism and distributing it to the separating units, and means for automatically reducing the flow of grain fed to the cleaning mechanism when the supply of grain in the receptacle is in excess of the normal capacity of the separating units.

45 9. In a machine of the character described the combination with a grain cleaning mechanism and a series of grain separating units, of a feeding device for feeding grain to the cleaning mechanism, a receptacle for receiving grain from the cleaning mechanism, said receptacle having a series of outlet ports for feeding the respective separating units, a distributing member in the receptacle for distributing the grain therein to the outlet ports, and means adapted to be actuated by the grain in the receptacle for automatically adjusting said feeding device when the machine is in operation.

50 10. In a machine of the character described the combination with a grain cleaning mechanism and a series of grain separating units, of a feeding device for feeding

55 grain to the cleaning mechanism, a receptacle for receiving grain from the cleaning mechanism, said receptacle having a series of outlet ports for feeding the respective separating units, a distributing member in the receptacle for distributing the grain therein to the outlet ports, and means adapted to be actuated by the grain in the receptacle for automatically adjusting said feeding device when the machine is in operation, and means 60 for manually actuating said automatic adjusting means.

11. In a machine of the character described the combination with a grain cleaning mechanism and a series of grain separating units, adapted to receive grain therefrom, of a feeding device for feeding grain to the cleaning mechanism, gates for controlling the flow of grain to the respective separating units, and means for simultaneously 65 opening and closing all of said gates.

12. In a machine of the character described the combination with a grain cleaning mechanism and a series of grain separating units, adapted to receive grain therefrom, of a feeding device for feeding grain to the cleaning mechanism, gates for controlling the flow of grain to the respective separating units, means for adjusting said feeding device and means for adjusting said 70 gates, said gate adjusting means being operative to actuate said feeding device adjusting means.

13. In a machine of the character described the combination with a grain cleaning mechanism and a series of grain separating units, adapted to receive grain therefrom, of a feeding device for feeding grain to the cleaning mechanism, gates for controlling the flow of grain to the respective 75 separating units, means for adjusting said feeding device and means for adjusting said gates, said gate adjusting means being operative to actuate said feeding device adjusting means, and said feeding device adjusting means being operable independently of the 80 gate adjusting means.

14. In a machine of the character described the combination with a grain cleaning mechanism and a hopper for supplying grain thereto, of a series of independently mounted gates for regulating the flow of grain to the cleaning mechanism from the hopper, springs for independently acting on said gates to hold them yieldingly closed, 85 and means for simultaneously adjusting all of said gates to regulate the discharge capacity of the hopper.

15. In a machine of the character described the combination with a grain cleaning mechanism and a hopper for supplying grain thereto, of a series of independently mounted gates for regulating the flow of grain to the cleaning mechanism from the hopper, springs for independently acting on 90

- 5 said gates to hold them yieldingly closed, and means controlled by the grain discharged from the cleaning mechanism for automatically adjusting all of said gates simultaneously.
- 10 16. In a machine of the character described the combination with a grain cleaning mechanism and a hopper for supplying grain thereto, of a closure for regulating the discharge opening of the hopper, and means adapted to be actuated by the grain discharge from the cleaning mechanism for automatically adjusting the hopper closure.
- 15 17. In a machine of the character described the combination with a grain cleaning mechanism and a hopper for supplying grain thereto, of a closure for regulating the discharge opening of the hopper, spring means tending to hold said closure in predetermined position, and means actuatable by grain discharged from the cleaning mechanism for automatically adjusting the closure and thereby control the flow of grain from the hopper.
- 20 18. In a machine of the character described the combination with a grain cleaning unit having a hopper for supplying grain thereto, of a shaft mounted in the unit, hopper gates carried by the shaft, springs associated with the shaft and gates to yieldingly act against the latter, and means for oscillating the shaft to vary the positions of the hopper gates.
- 25 19. In a machine of the character described the combination with a grain cleaning unit having a hopper for supplying grain thereto, of a shaft mounted in the unit, hopper gates carried by the shaft, springs associated with the shaft and gates to yieldingly act against the latter, and means actuatable by the grain discharged from the cleaning unit for oscillating the shaft to regulate the positions of the gates.
- 30 20. In a machine of the character described the combination with a grain cleaning mechanism and a grain separating mechanism, of a receptacle for receiving grain from the cleaning mechanism and delivering it to the separating mechanism, means for delivering grain to the cleaning mechanism, and means adapted to be actuated by an excess supply of grain in the receptacle for adjusting the delivering means.
- 35 21. In a machine of the character described the combination with a grain cleaning mechanism and a grain separating mechanism, of a receptacle for receiving grain from the cleaning mechanism and delivering it to the separating mechanism, means for delivering grain to the cleaning mechanism, and means adapted to be actuated by an excess supply of grain in the receptacle for adjusting the delivering means, said last mentioned means comprising a conveyor and a plate adjustably associated therewith.
- 40 22. In a machine of the character described the combination with a grain cleaning mechanism and a series of grain separating units, of a receptacle for receiving grain from the cleaning mechanism, said receptacle having a discharge port for each separating unit, a conveyor for moving the grain in the receptacle over said ports, and means near one end of the receptacle for engagement by the grain therein for controlling the volume of grain fed to the cleaning mechanism.
- 45 23. In a machine of the character described having a grain cleaning mechanism and a series of grain separating units, the combination including a receptacle for receiving grain from the cleaning mechanism, said receptacle having a discharge port for each separating unit, a conveyor for moving the grain in the receptacle over said ports, a plate adjustably carried in one end of the receptacle, and an operative connection between the plate and means for feeding grain to the cleaning mechanism.
- 50 24. In a machine of the character described having a grain cleaning mechanism and a series of grain separating units, the combination including a receptacle for receiving grain from the cleaning mechanism, said receptacle having a discharge port for each separating unit, means for feeding grain to the cleaning mechanism, a plate member adjustably mounted in the receptacle, and adapted to be moved by a surplus amount of grain therein, for adjusting said feeding means.
- 55 25. In a machine of the character described having a grain cleaning mechanism and a series of grain separating units, the combination including a receptacle for receiving grain from the cleaning mechanism, said receptacle having a discharge port for each separating unit, means for feeding grain to the cleaning mechanism, a plate member adjustably mounted in the receptacle, and adapted to be moved by a surplus amount of grain therein, for adjusting said feeding means, and means for manually moving said plate member to effect an adjustment in said feeding means.
- 60 26. In a grain treating machine having a primary grain treating mechanism and a secondary grain treating mechanism, the combination of means for controlling the supply of grain to the primary treating mechanism, means for delivering grain from the primary treating mechanism to the secondary treating mechanism, and means, associated with the delivering means, for automatically adjusting said controlling means when the supply of grain to the secondary treating mechanism exceeds the capacity thereof.
- 65 27. In a grain treating machine having a primary grain treating mechanism and a

secondary grain treating mechanism adapted to receive grain from the primary treating mechanism, the combination of means for controlling the supply of grain to the primary treating mechanism, and means adapted to be influenced by the grain passing to the secondary treating mechanism for automatically adjusting the said grain con-

trolling means to reduce the supply of grain to the primary treating mechanism when 10 the supply of grain passing therefrom to the secondary treating mechanism exceeds the predetermined capacity of the latter.

In testimony whereof I affix my signature.

CARL C. GRAY.
